UNITED STATES PATENT OFFICE

ALFRED G. F. KUROWSKI, OF BROOKLYN, NEW YORK, ASSIGNOR TO UNDERWOOD ELLIOTT FISHER COMPANY, OF NEW YORK, N. Y., A CORPORATION OF DELAWARE

TYPEWRITING MACHINE

Application filed December 18, 1926. Serial No. 155,609.

This invention relates to typewriting machines of that class where a platen-lever is operable to sweep the platen forwardly or rearwardly greater distances than the usual line-spacing mechanism.

This novel device is adapted for application to standard typewriters, and includes an adjustable platen-sweep handle on the platen-frame and operatively connected to the platen 10 by means of a pawl which is resiliently held in engagement with a ratchet-wheel. This pawl may be locked in permanent engagement by means of a dog, so that the platen-sweep handle will rock the ratchet-wheel and the platen 15 therewith, during the return movement thereof.

It is practicable for an operator to first insert a card or a sheet into the machine, at the rear of the platen, and then operate the handle to sweep the platen and work-sheet to the printing line, then type a line of printing, and finally return the handle to the starting point, thereby rolling the platen rearwardly with the typed work-piece, which is carried back 25 out of the machine.

When the handle is restored to its normal position, the locking dog and pawl are released from said ratchet-wheel, and the platen may be rotated freely by the usual 30 platen-knob, or line-spaced by the usual line-space mechanism, making it possible to operate the typewriter for ordinary work such as letter writing.

One of the features of this invention is that 35 the locking dog is not only effective to positively lock the pawl in tooth-interlocking position to swing the ratchet-wheel therewith during the return movement of the handle, but is also effective to positively prevent overthrow of the platen when the handle is operated forwardly against a stop.

It will be understood that this device can be used for performing two kinds of special 45 work-sheet feeding work in addition to the regular line-spacing of the work-sheet. Moreover, the same equipment can be applied to different machines and perform one kind of work in one machine and another kind in 50 another machine, thus making it unnecessary

to carry a stock of two kinds of platen-controlling attachments.

In order that the device may be used for typing a connected series of forms of uniform lengths, the locking dog is provided 55 with a handle whereby it may be automatically released at the end of the forward stroke of the sweep-handle, so that throughout said return stroke thereof the platen will remain stationary, the pawl riding freely back over 60 the teeth of said ratchet-wheel.

This invention may be regarded as an improvement on my pending application filed June 28, 1926, Serial No. 118,996 (now Patent No. 1,752,491, dated April 1, 1930). 65

Other features and advantages will hereinafter appear.

In the accompanying drawings, Figure 1 is a perspective view showing the new device as applied to an Underwood type-writing machine. 70

Figure 2 is a side view, in elevation, showing the same device in its normal position, the platen being free to be rotated.

Figure 3 is a conventional cross-sectional 75 view showing some of the mechanism displaced for the purpose of illustration.

Figure 4 is a diagrammatic view showing the driving pawl in its locked position, so as to carry the platen in forward and return 80 movements of the handle.

Figure 5 is a diagrammatic view showing the pawl in its released position and illustrates how the handle may be moved back without moving the platen therewith. 85

This device may be employed for handling cards or single work-sheets to be inserted at the rear of a platen 10, rotatably mounted in end frames 11 of a platen-frame. A handle 12 is moved forwardly to thereby sweep the work-sheet to the printing line. The handle is pivotally mounted upon a stud 13 fast to a supporting side plate 14 and carries a pawl 15 designed to engage a ratchet-wheel 16 loosely mounted to rotate about the stud 13. The 90 pawl is mounted upon a screw 17 fast to the handle, and is held in engagement with the teeth of the ratchet-wheel by means of a spring 18 which serves also as a means for operating a locking dog 19 mounted upon the 100

handle by means of a pivot-screw 20. The ratchet-wheel 16 is operative to drive a spur-gear 21 and a pinion 22 fast to the free end of a platen-axle 23.

5 Normally the pawl 15 and the locking dog 19 are held in ineffective positions by means of stop-pins 24 and 25 carried by a stop-plate 26 which is pivotally mounted upon the stud 13 and may be adjustably positioned and held 10 in place by means of a locking pawl 27, which normally engages the teeth of a fixed toothed plate 28 and is itself carried by the stop-plate 26 by means of a stud 29. The normal or ineffective position of the handle is shown in 15 Figure 2. When the handle 12 is pulled forwardly to rotate the platen, the pawl 15 is released from the stop 25, and the spring 18 becomes effective to throw the pawl into engagement with the ratchet-wheel, as shown 20 in Figure 4. The handle is then moved all the way forwardly until it is arrested by a stop or rod 30. This determines the position of the card at the printing line, and, after 25 typing, the handle may be moved backwardly to its normal position, thereby ejecting the card. It is the variable relation between the stationary stop-pin 30 and the adjustable carrier-plate 26 and its pins that definitely 30 determines the handle-throw and platen-rotation. The number of line-spaces that the platen is rotated during a complete movement of the handle is indicated by a graduated scale 31 which co-operates with an index 32 secured on the stop-plate 26. The scale 35 is fast to the plate 14.

On the other hand, in order that this device may be used for the handling of continuous forms which require the feeding of the platen forwardly a predetermined uniform 40 number of line-spaces, the locking dog 19 is provided with a handle 33 which serves as a means for disengaging the dog from the pawl to thereby permit a sliding return movement of the pawl over the ratchet-teeth during 45 the return movement of the handle. This condition is illustrated in Figure 5, in which it will be noticed that the locking dog is held against a pin 34 by means of the thumb while the handle is controlled by the other fingers 50 of the hand. The handle is held in its ineffective position by means of a spring 35 encircling a spring-drum 36 carried by a handle-hub or sleeve 37. One end of the spring is secured to the drum by means of a 55 pin 38. The other end of the spring is anchored on a pin 39 carried by the plate 14. The handle 12 is, of course, operative independently by its grip or finger-piece 49, without engaging finger-piece 33, except when 60 desired.

This device is preferably made in the form of an attachment to a standard typewriter. To this end, and to the end that the device may be carried in stock as a unit, all the 65 mechanism is permanently assembled and

adjusted between the plate 14 and the toothed plate 28 which plates are held together by means of a tie-rod 40 and the stop-rod 30. The toothed plate 28 is provided with an extension 41 which serves as a bearing for a short shaft 42. The latter carries at the end thereof a finger-wheel 43 for rotating the platen. The finger-wheel 43 and the pinion 22 are both fast to the shaft 42 by means of screws 44 and 45, one at each side of the plate 28 so that when a screw 46 which secures the pinion 22 to the platen-axle is loosened the pinion and the finger-wheel may be taken off the platen-shaft of the machine together with the other mechanism. It will be particularly noted that there is also disclosed a factory assembled and factory adjusted, self-contained, platen-driving mechanism attachable as an assembled unit to any Underwood typewriting machine; that the foot 47 of one side plate 14 may be attached to the carriage by two displaceable screws 48 entering factory threaded holes in the carriage-end 11, and the hub of the pinion 22 engaging the short projecting end of the platen-shaft 23 by the screw 46 becomes a coupling effective to axially connect the original platen-shaft 23 with the auxiliary shaft 42 and lengthen the original platen-shaft, so that the platen may be driven by the pinion 22 or rotated by the finger-wheel 43; that the lengthening of the platen-shaft 23 by the means provided in the attachment removes the necessity for replacing the original platen-shaft by a new and longer one-piece shaft and which displacement is especially objectionable where the platen is provided with a factory assembled frictional line-spacing mechanism; and that the operating handle 12 carries a one-way platen-driving pawl 15 and further carries a manually-operated pawl-controlling trip 19 effective to render the one-way driving pawl effective to rotate the platen forwardly and then backwardly to effect a paper-inserting and a paper-ejecting operation, or to rotate the platen forwardly for a paper-inserting operation only, and permit the pawl 15 to drag idly over the platen-driving toothed wheel 16, back to a normal platen-released position.

Variations may be resorted to within the scope of the invention, and portions of the improvements may be used without others.

Having thus described my invention, I claim:

1. In a platen-sweeping mechanism for feeding a work-sheet into a typewriting machine, the combination with a pinion on the platen-shaft, a gear in train to drive said pinion, a ratchet-wheel to drive said gear, an operating lever, and a pawl on said lever normally disengaged from said ratchet-wheel but released during the initial forward swing of said lever to engage said

ratchet-wheel and rotate said platen-shaft, of pawl-locking means mounted upon said operating lever and rendered effective by the release of said pawl to lock said pawl in 5 engagement with the ratchet-wheel, and a spring connecting said pawl with its locking means and effective to throw the pawl into engagement with the ratchet-wheel and throw the locking means into interlock with 10 the pawl, said locking means also having a pawl-releasing device manually operable at the end of the forward sheet-feeding movement of the platen to forcibly release the locked pawl and allow the operating lever to 15 be returned to normal position, and independently of the platen.

2. In a platen-sweep mechanism attachable as a preassembled unit of mechanism to one carriage-end and to the projecting end 20 of a platen-shaft without disassembly of the unit, said unit including a pair of spaced-apart side plates, one plate secured to the carriage-end with replaceable screws, the other plate forming a bearing for an extension-shaft 25 maintained in said bearing between a coupling connectible to the platen-shaft end and a finger-wheel, said coupling formed with a pinion to be driven by a train of connected mechanisms, including a pinion- 30 driving multiplying gear, a toothed wheel for driving said gear, an operating handle, a one-way pawl on said handle spring-pressed in the direction of the toothed-wheel, a back-stop rockably mounted upon the axis of the 35 handle and operative to disable the pawl at normal position against its spring, mechanism 40 operable to set the back-stop to predetermine the extent of platen-rotation to a fixed stop on the frame, a drum fixed to rotate with the handle, a spring having one end fixed to the drum and the other end fixed to the frame and assembled under a tension operative to restore the operating handle to its 45 normal pawl-disabling position when released by the handle after a forward platen-sweeping operation, and means pivotally mounted upon the operating handle and spring-pressed into co-operation with the one-way pawl to render the pawl effective as 50 a locked-up two-way pawl to drive the toothed-wheel forward and back to rotate the platen in two directions, said means being engageable with the same back-stop and jointly disabled with the pawl at the normal position 55 of the operating handle.

3. In a platen-sweep mechanism attachable as a preassembled unit of mechanism to one carriage-end and to the projecting end of a platen-shaft without disassembly of the unit, 60 said unit including a pair of spaced-apart side plates, one plate secured to the carriage-end with replaceable screws, the other plate forming a bearing for an extension-shaft maintained in said bearing between a coupling 65 connectible to the platen-shaft end and a fin-

ger-wheel, said coupling formed with a pinion to be driven by a train of connected mechanisms, including a pinion-driving multiplying gear, a toothed-wheel for driving said gear, an operating handle, a one-way pawl on said handle spring-pressed in the direction of the toothed-wheel, a back-stop rockably mounted upon the axis of the handle and operative to disable the pawl at normal 70 position against its spring, mechanism operable to set the back-stop to predetermine the extent of platen-rotation to a fixed stop on the frame, a drum fixed to rotate with the handle, a spring having one end fixed to the drum and the other end fixed to the frame and assembled under a tension operative to restore the operating handle to its normal pawl-disabling position when released by the hand after a forward platen-sweeping operation, and means pivotally mounted upon the operating 75 handle and spring-pressed into co-operation with the one-way pawl to render the pawl effective as a locked-up two-way pawl to drive the toothed-wheel forward and back to rotate the platen in two directions, said means being engageable with the same back-stop and jointly disabled with the pawl at the normal position of the operating handle, said means also including a disabling arm operative to release the locked-up pawl at the end of the forward 80 stroke of the handle to provide an idling sweep of the pawl to its back-stop position.
